UNITED STATES PATENT OFFICE.

FRANK GILBERT HINSDALE, OF NEW YORK, N. Y.

MACHINE FOR DOFFING LACE FABRICS.

Original application filed January 12, 1923, Serial No. 612,176. Divided and this application filed February 18, 1926. Serial No. 89,016.

My invention relates to the manufacture of lace fabrics such as lace curtains, and has for its object to provide a novel and simple apparatus of simple construction and operation, whereby the doffing of the lace fabric from the loom may be efficiently carried out. The invention contemplates particularly the provision of a winding apparatus of the indicated type which is portable and capable 10 of being easily shifted about. Other objects of the invention will appear from the description hereinafter and the features of novelty will be pointed out in the claims. The present application is a division of another application filed by me on January 12, 15 1923, Serial No. 612,176.

Reference is to be had to the accompanying drawings, which illustrate examples of the invention without defining its limits, 20 and in which Figs. 1 and 2 illustrate the manner in which the lace leaves the loom; Fig. 3 illustrates diagrammatically the utility of the doffing machine; Fig. 4 is a side elevation of the machine; Fig. 5 is a sectional elevation thereof; Fig. 6 is an end view of the improved apparatus, and Fig. 7 is a horizontal section thereof.

In order that the invention may be easily understood, reference will be had to the diagrammatic illustrations of Figs. 1, 2 and 3. The curtains may be woven in the usual manner lengthwise of the loom, there being, at times, as many as one hundred curtains located side by side in one piece of weaving; 35 wherever the woven piece consists of two or more curtains they will, according to the present invention, be split apart into individual curtains directly on the loom after weaving and prior to being passed to the so-called batch-roll of the loom. That is to say, the piece of woven material *a*, Fig. 1, consisting of a plurality of individual curtains is passed over knives 20 located upon the breast-beam 21 of the loom in registry 40 with the lines of division between adjacent curtain widths, or in a manner to split the lace into individual curtains of any predetermined width. After having been split by the knives 20 into individual width of 45 curtains *a'*, Fig. 2, the latter are batched by being passed over suitably driven porcupine-rolls 22, and wound up on tubes 23, each of which is of suitable length to accommodate one curtain width and all of which are loosely mounted upon the batch-roll beam 24 of

the loom, as shown diagrammatically in Fig. 2. As the next step, the curtains are doffed from the loom in the following manner: After the batch-roll beam 24 has been shifted to throw the rolls of curtains *a'* out of contact with the porcupine-rolls 22, the first width of curtain *a'*, for instance at the left-hand end of Fig. 2, is threaded around a tension bar 25, Fig. 3, and nipped between a doffing machine roll 26 and a spit-bar on winding core 27 normally lying in surface contact therewith. The doffing machine roll 26 is then driven for instance at a speed of approximately two hundred yards per minute, which causes the lace from the first tube 23 to be rolled upon the spit-bar 27, which gradually moves away from the roll 26 in a predetermined path as the winding proceeds. As soon as the lace has been completely unwound from the first tube 23, the next width of curtain *a'* on the second tube 23 is similarly wound upon the bar 27 and added to the lace previously wound thereon. This operation is repeated until the loom is entirely doffed of lace, leaving one large roll *b* of lace commonly termed a section and consisting of the individual lengths taken from the plurality of small rolls previously on the loom. This large roll *b* of lace may then be passed along to any predetermined point to carry on the method of manufacturing the curtains. The aforesaid doffing of the lace is conveniently and efficiently carried out by means of the doffing machine illustrated in Figs. 4, 5, 6 and 7, and comprising a horizontal supporting frame 28, preferably mounted upon casters 29 or their equivalent to render the machine portable and permit it to be readily and easily shifted about as required. The frame 28 is provided with uprights 30 spaced apart in registry with each other and fixed in place in any convenient manner, as by bolts 31, said uprights being slotted lengthwise as indicated at 32 in Figs. 5 and 6. Bearings 33 are mounted upon said uprights 30, preferably by being pivotally hung between bearing screws 34 located in co-operating pairs upon each upright, as shown in Fig. 7, and constitute journals for the shaft 35 of a drum 36, which is suitably fixed upon said shaft, for instance by set screws or the like. The drum 36 may be of any convenient construction and preferably comprises a cylinder consisting of segments of wood 105 110

lagging secured upon spiders 37, whereby the drum is mounted upon the shaft 35, the surface of the drum being preferably covered with a winding of cord 38 or otherwise treated to increase the frictional effect thereof. The drum 36 is rotatably driven in any convenient manner, as by means of an electric motor 39 carried upon the frame 28 and provided upon its shaft with a pinion 40 arranged in mesh with a gear 41 secured upon an intermediate shaft 42 suitably journaled in one of said uprights 30; the intermediate shaft 42 further carries a pinion 43 which meshes with a gear 44 fixed upon the drum shaft 35 and whereby power is transmitted thereto. The doffing machine now being described further includes means for maintaining the spit-bar 27 and the roll of lace carried thereby in operative relation to the drum 36, provision being made to permit the bar 27 to move away from said drum as the roll of lace gradually increases in diameter. In the illustrated example the means referred to comprises duplicate latch members 46 provided with recesses 47 for the reception of the ends of said spit-bar 27 and having lugs 48 projecting from said recesses for a purpose to be more fully set forth hereinafter. The latch members 46 include suitable manipulating handles 49 and are pivoted at 50 upon slides 51 fitted to slide vertically in the slots 32 of the uprights 30, suitable stops 52 being provided for arresting the pivotal movements of said latch members in one direction. The slides themselves may be slidably fixed in said slots by means of plates 53 clamped in place by means of clamp screws 54; as shown in the drawings, the clamp screws 54 may comprise integral parts of the stops 52, it being understood that, normally, the clamp screws 54 serve to maintain the parts of the slides in operative connection without interfering with the sliding movements thereof in the slots 32, but that when the screws are tightened they clamp the slides together to prevent such sliding movement. If desired, liners of fibre or other suitable material may be located between the slides 51 and the uprights 30 and between said slides and the plates 53.

In practice, the motor 39, through the medium of the gearing 40, 41, 43 and 44, serves to rotatably drive the drum 36 which, in turn, because of its surface engagement with the spit-bar 27, transmits its motion to the latter and thus causes the lace α' to be wound up on said bar 27 and withdrawn from successive tubes 23, the doffing machine being easily shifted upon the casters 29 into operative relation with each tube upon the loom. As the doffing proceeds and the diameter of the roll of lace being wound upon the spit-bar 27 increases, thus causing the latter to gradually move away from the

drum 36, the slides 51 will correspondingly rise in the slots 32; during this operation the ends of the spit-bar 27 are journaled in the recesses 47 of the latch members 46 and are held thereby against displacement whereby the roll of lace being doffed is maintained in proper operative relation to said drum 36. When the doffing operation has been completed, the clamp screws 54 are tightened, and the handles 49 are thrown to rotate latch members 46 on their pivots 50, causing the lugs 48 to raise the spit-bar 27 and its roll of lace β , whereby the latter is lifted away from the drum 36 a sufficient distance to clear the same; in this position of the latch members 46, the recesses 47 are outwardly open, so that the spit-bar 27 may be rolled forwardly on said lugs 48 and easily removed from the machine with the roll of lace β .

The doffing machine illustrated and described exemplifies mechanical means whereby the operation of doffing the curtains may be efficiently and successively carried out.

Because of the portability of the doffing machine, it may easily be shifted about as required and thus reduces the doffing operation and the transfer of the doffed lace subsequent to the doffing, to the simplest operation requiring little manual effort and no particularly skilled supervision.

Various modifications in the mechanism shown and described may be made within the scope of the claims without departing from the nature of my invention.

I claim:

1. A machine for doffing lace curtains comprising a portable support, a drum journaled thereon, uprights on said support and provided with slots, a spit-bar adapted to be operated by said drum to wind up the lace in the form of a roll, blocks slidably mounted in said slots, latch members pivotally mounted upon said blocks and constituting bearings for said spit-bar, and a motor carried by said support and operatively connected with said drum to actuate the same.

2. Winding apparatus for fabrics, comprising a frame, a rotatable drum journaled therein, a pair of slides mounted in said frame, latch members pivoted to said slide, a spit-bar removably journaled in said latch members in a position to be rotated by said drum for winding the fabric in the form of a roll, and means on said latch members whereby the completed roll of fabric may be shifted clear of said drum for removal from the apparatus.

3. Winding apparatus for fabrics, comprising a frame, a rotatable drum journaled therein, a pair of slides mounted in said frame, latch members pivoted to said slide and provided with recesses, a spit-bar removably journaled in said recesses and adapted to be rotated by said drum for

winding the fabric in the form of a roll, and lugs forming part of said latch members for exerting a lifting action on said spit-bar whereby the completed roll of fabric is lifted clear of said drum for removal from said apparatus, said lugs constituting supports on which the spit-bar with the roll of fabric may be rolled to disconnect said spit-bar from said latch members.

4. Winding apparatus for fabrics, comprising a portable frame, a rotatable drum journaled therein, a pair of members slidably mounted in said frame, latch members pivoted to said slidable members and provided with recesses, a spit-bar removably journaled in said recesses and adapted to be rotated by said drum, for winding the fabric in the form of a roll, lugs comprising extensions of said latch members adjacent to said recesses and arranged to exert a lifting action on said spit-bar whereby the roll of fabric is lifted clear of the drum for removal from the apparatus, said lugs constituting supports on which said spit-bar may be rolled out of said recesses to disconnect the roll of fabric from said latch members, means for holding said slidable members in fixed position during the removal of said roll of fabric.

In testimony whereof I have hereunto set my hand.

FRANK GILBERT HINSDALE.
